UNITED STATES PATENT OFFICE.

ROBERT A. ROBERTSON, OF ROCKSPRINGS, TEXAS.

WATER MOTOR.

Application filed May 29, 1926. Serial No. 112,614.

This invention relates to water wheels designed for use in connection with water motors and aims to provide a novel form of wheel which will be exceptionally efficient 5 in operation and one wherein the water directed to the blades of the wheel will impinge upon the blades in such a way as to obtain the maximum amount of force from the water.

10 Another important object of the invention is to provide a water wheel provided with means for maintaining the blades in a heated condition so that the wheel may be operated during freezing weather, eliminating ice on 15 the wheel to retard the movement thereof.

With the foregoing and other objects in view which will appear as the description proceeds, the invention resides in the combination and arrangement of parts and in the 20 details of construction hereinafter described and claimed, it being understood that changes in the precise embodiment of the invention herein disclosed, may be made within the scope of what is claimed, without departing 25 from the spirit of the invention.

Referring to the drawing:

Figure 1 is a fragmental elevational view of a water wheel constructed in accordance with the invention.

30 Figure 2 is a sectional view taken on line 2—2 of Figure 1.

Figure 3 is a fragmental sectional view through one of the blades of a modified form of water wheel.

35 Referring to the drawing in detail, the water wheel forming the essence of the invention includes end sections, each of which end sections comprises a hub 5 to which the spokes 6 are secured, which spokes are 40 formed of channel iron, in the present showing, however it is to be understood that these spokes may be constructed of any suitable material such as piping or the like.

A substantially wide curved member 7 is 45 connected to the spokes adjacent to the outer ends thereof and form a part of each end section, the end sections are held in spaced relation with each other by means of the blades, which blades include curved plates 8 and vertical box-like members 9 against 50 which the water impinges to cause the rotation of the wheel.

Within the box-like portion 9 is an electric heating element 10 constructed to maintain the box-like portion 9 in a heated condition 55 at all times and prevent the formation of ice on the wheels to the end that the device may be efficiently used in freezing weather without danger of ice collecting on the wheel to retard its movement. 60

While the wires and source of electric supply have not been shown in the present drawing, it is to be understood that any suitable connection may be made between a source of electric supply and the heating 65 coils 10 of the wheel to accomplish the purpose of the invention.

As shown, Figure 3, the members 11 corresponding to the members 7 in Figure 1, are held in spaced relation by means of the 70 plates 12 which have integral laterally extended flanges 13, the plates 12 being secured to the members 11 by means of the angle bars 14 that in turn are secured to the members 11. 75

As illustrated, the flanges 13 are curved to conform to the periphery of the members 11 to the end that water dropped onto the flanges 13 will act to move the wheel in a vertical plane to rotate the shaft on which the 80 same is positioned.

From the foregoing it will be obvious that due to the construction, I have provided a novel water wheel construction and one in which the ice will be prevented from collecting in freezing weather. 85

I claim:

In a water wheel, a shaft, an elongated hub on the shaft, spokes secured to the ends of the hub and radiating therefrom, substantial wide circular members secured to the spokes adjacent to the outer ends thereof, housings supported between the circular members, each of said housings embodying a pair of spaced plates, one of the plates of 90 each housing having a laterally extended flange curved to conform to the curvature of the circular members, said flanges being disposed adjacent to the peripheries of the circular members, and heating elements supported within the housings. 95

In testimony that I claim the foregoing as my own, I have hereto affixed my signature.

ROBERT A. ROBERTSON.
